UNITED STATES PATENT OFFICE.

MACK H. DAVIS, OF FINIS, TEXAS, ASSIGNOR OF ONE-HALF TO JOHN W. NOE, OF FINIS, TEXAS.

FRUIT-CUTTING IMPLEMENT.

1,313,273.

Specification of Letters Patent. Patented Aug. 19, 1919.

Application filed May 13, 1918. Serial No. 234,188.

To all whom it may concern:

Be it known that I, MACK H. DAVIS, a citizen of the United States, residing at Finis, in the county of Jack, State of Texas, have invented certain new and useful Improvements in Fruit-Cutting Implements; and I do hereby declare the following to be a full, clear, and exact description of the invention, such as will enable others skilled 10 in the art to which it appertains to make and use the same.

This invention relates to improvements in fruit cutting implements and particularly to devices for splitting lemons.

15 One object of the present invention is to provide a novel and improved device of this character whereby a lemon or other similar fruit can be quickly and effectively cut into two equal parts, preparatory to the 20 squeezing thereof.

Another object is to provide a novel and simple device of this character which will avoid the usual and dangerous practice of cutting the lemons with a knife, as well as 25 to greatly increase the speed with which the lemons can be cut.

Other objects and advantages will be apparent from the following description when taken in connection with the accompanying 30 drawing.

In the drawing:

Figure 1 is a perspective view of the device in open position, and looking from the pivotal end of the device.

35 Fig. 2 is a vertical longitudinal sectional view taken on the line 2—2 of Fig. 1.

Referring particularly to the accompanying drawing, 10 and 11 represent a pair of levers which are pivotally connected to 40 gether at one end, as shown at 12. Intermediate the ends of the lever 10 there is formed a flat diskal portion 13, and extending at right angles from the inner face of said portion is a block 14. In the end face 45 of the block there is formed a recess 15 which is adapted to receive a portion of the lemon to be squeezed, as will be more fully explained hereinafter. Formed longitudinally through the center of the block 50 is a kerf or slot 16 which divides the block into two portions, as is clearly shown in the drawing. At a corresponding portion

in the lever 11 there is formed an enlarged ring portion, the inner face of which is inclined transversely of the depth of the ring, as shown at 17, whereby a partial socket is formed for the reception of a portion of the lemon to be squeezed. Extending longitudinally within the ring, and at the outer portion thereof, is a knife blade 18, the ends of which are secured in the slots 19, by means of the transverse rivets or pins 20. The edge of the knife blade, within the ring, or that edge which is directed toward and which is received in the kerf of the block 14, when the levers are brought together, is formed with a point 21, the portions of this edge inclining longitudinally in opposite directions away from said point. Thus the knife blade will be 70 better able to get a start into the lemon when the levers are brought together.

It will thus be seen that when a lemon is placed in the inner portion of the ring, and the lever 10 moved toward said ring, the block 14 will engage the lemon and push the same against the knife blade with the result that the lemon will be cut into two parts and pushed through the ring. Thus the lemon can be more quickly and effectively cut than where a knife is used. Also, 80 the danger to the fingers of the operator is eliminated.

There is thus provided a novel and simple device by means of which lemons, as well as other similar small fruit, can be cut preparatory to squeezing the juices therefrom, and without danger to the fingers of the operator. Furthermore, the speed with which the fruit can be cut is greatly increased over 90 the old method of using a knife.

What is claimed is:

1. A fruit cutting implement including a pair of movably connected levers, one of said levers having a substantially triangular cutting member, the other lever being provided with an elevated and recessed member for supporting the fruit and pushing the fruit against the cutting member, said elevated member being divided for passage on opposite sides of the cutting member. 95

2. A fruit cutting implement including a pair of pivotally connected levers, one of

the levers having an intermediate disk portion formed with an elevated extending block having a longitudinal kerf, said block being formed with a lemon receiving recess in the end face thereof, the other lever being formed intermediately with a ring portion having its inner face inclined, and a longitudinally extending substantially tri-

angular knife blade secured within the ring and arranged for reception in said kerf. 10

In testimony whereof, I affix my signature in the presence of two witnesses.

MACK. H. DAVIS.
